Everett Rook, ATTORNEYS

UNITED STATES PATENT OFFICE.

WILLIAM E. EDWARDS, OF IRVINGTON, NEW JERSEY.

STAND FOR CIGARETTES AND THE LIKE.

Application filed April 15, 1921. Serial No. 461,522.

To all whom it may concern:

Be it known that I, WILLIAM E. EDWARDS, a citizen of the United States, and a resident of Irvington, in the county of 5 Essex and State of New Jersey, have invented new and useful Improvements in Stands for Cigarettes and the like, of which the following is a specification.

This invention relates to stands or supports for cigarette holders, cigar holders, pipes, fountain pens and the like, for preventing the same from rolling on a flat surface, such as a table or desk, and maintaining them in spaced relation thereto, thereby 10 by eliminating the possibility of the supporting surface becoming burned or otherwise injured or marred.

The objects of the invention are to provide a device of the character described 15 adapted to be supplied to a cigarette holder, cigar holder, fountain pen, pipe stem or like articles, to support the same at a plurality of points longitudinally thereof and at a plurality of points upon opposite sides 20 of the longitudinal median line thereof to space the cigarette, fountain pen or the like from a supporting surface and prevent both longitudinal tilting and rolling of the same over the said surface; to provide 25 such a device having a pair of props adapted to extend longitudinally of the article in spaced relation to prevent longitudinal tilting of said article; to provide each of said props with a pair of feet disposed upon opposite sides of the longitudinal 30 median line of the article to prevent rolling thereof; to provide means for pivotally connecting said props on the article whereby they may be swung longitudinally 35 thereof into spaced relation in operative position or nested together in a compact relation closely against the article in an inoperative position; to thus provide a sleeve or band adapted to be applied to an article 40 circumferentially thereof and having a prop 45 connected to each edge thereof in substantial alinement; to form said band with pivot sleeves to receive the props so that the props may swing in opposite directions 50 into spaced relation; to construct the said props so that one may be received within the other in a nested relation closely adjacent the article when they are swung toward each other; and to obtain other re-

sults and advantages as may be brought out 55 by the following description.

Referring to the accompanying drawings, in which like numerals of reference indicate the same parts throughout the several views,

Figure 1 is a perspective view of a cigarette holder having a stand constructed in accordance with my invention applied thereto and shown in operative position;

Figure 2 is an enlarged plan view of the 60 stand and the cigarette holder, showing the stand in an inoperative position;

Figure 3 is a similar view showing the stand extended into an operative position;

Figure 4 is a vertical longitudinal sectional view through the stand shown in operative position, the cigarette holder being shown in side elevation, and

Figure 5 are transverse vertical sectional views through the cigarette holder and one 70 of the pivot sleeves for the props showing the operation of the spring arms of the props in the pivot sleeve.

For the purposes of illustration I have shown the stand embodying my invention 80 used in connection with a cigarette holder for spacedly supporting the cigarette on a surface, such as a table or desk, to hold the same against longitudinal tilting and rolling to prevent burning of the surface 85 by the lighted end of the cigarette. On the drawings I have shown the stand as comprising a split band 1 of resilient metal which is adapted to be applied circumferentially of the article to be supported, 90 the said band being formed at one edge thereof opposite the split with an integral sleeve 2, the ends of which at the lower sides thereof are formed with curved extensions 3. At the opposite edge of the band 1 an integral extension 4 is provided, the extremity of which is formed into a sleeve 5 similar to the sleeve 2. These sleeves 2 and 5 serve as pivots for the props 95 6 and 7 which support the article. Each 100 of the props is preferably formed of resilient wire bent into a substantially U-shape and having its extremities bent at substantially right angles to the arms thereof as at 8 to form pivot studs to enter the 105 ends of the respective sleeves 2 and 5, pivot studs being held in position within the sleeves by the spring action of the arms of

the prop. The props 6 and 7 are thus adapted to swing longitudinally of the article to which the stand is applied. The prop 6 is substantially larger than the prop 7 and its closed end is curved as at 9 to conform to the curvature of the article to which the stand is applied when the prop is swung against the band 1, as shown in Figure 2. When the prop 6 is swung away from the band 1 into the position shown in Figures 3 and 4 the curved portion 9 thus engages the article, in the present instance the cigarette holder 10, so as to space the junction points 11 of the curved portion 9 with the arms of the prop from the article. In this position the said junction points 11 serve as feet which are arranged upon opposite sides of the longitudinal median line of the cigarette holder. The prop 7 is similar in construction to the prop 6 but slightly smaller and is provided at its closed or swinging end with a curved portion 12 similar to the portion 9 of the prop 6 which when swung into the position shown in Figures 3 and 4 engages the article 10 similarly to the prop 6, the junction points 13 of the portion 12 with the arms of the prop serving as feet similarly to the feet 11 of the prop 6. It will thus be seen that with the two props in the position shown in Figures 3 and 4 the respective feet 11 and 13 are arranged in spaced relation longitudinally of the article 10 so as to prevent longitudinal tilting thereof, the said feet 13 and 11 of the respective props being also arranged upon opposite sides of the longitudinal median line of the article so as to prevent rolling thereof. To swing the props into inoperative position the prop 7 is first swung against the band 1, after which the prop 6 is also swung against the band, receiving the prop 7 within itself, the said props being thus arranged in a nested relation closely adjacent the article 10.

The props 6 and 7 when in an operative position will maintain a cigarette and holder or the like, spaced throughout its length from a support so as to prevent burning or marring of the supporting surface and also prevent the bit of a cigarette holder, pipe or the like from becoming contaminated by contact with the support. It will be observed that the band 1 being formed of resilient material, the extension 4 thereof will serve as a spring arm tending to draw the band 1 into snug engagement with the article, the said extension thus increasing the frictional engagement of the band with the article to hold the same against longitudinal movement thereon.

The curved extensions 3 at the ends of the pivot sleeves serve as stops to hold the props in both operative and inoperative positions. As the props are swung in the pivot sleeves from one side thereof to the other, the arms

thereof spring over the extensions 3, and after passing said extensions snap inwardly against the ends of the sleeve, the said curved extensions 3 thus holding the props in one position or the other until they are 70 forcibly moved in the opposite direction. This cooperation of the extensions 3 of the sleeves and the spring arms of the props is clearly shown in Figure 5 of the drawings.

The stand has been shown and described 75 in connection with a cigarette holder, but it will be understood that it may as well be used with fountain pens for maintaining the point of the pen in spaced relation to a support and prevent rolling thereof, and can 80 also be used with tobacco pipes or other articles which it is desired to support upon a flat surface in spaced relation thereto and hold against rolling. Obviously, many 85 modifications and changes can be made in the detail construction of the stand without departing from the spirit or scope of the invention, and I do not desire to be understood as limiting myself except as required by the following claims when construed in 90 the light of the prior art.

Having thus described the invention, what I claim is:

1. A stand of the character described including a member to be attached to an 95 article to be supported, and a pair of props pivotally connected to said member and adapted to swing into spaced relation longitudinally of said article to support the same.

2. A stand of the character described including a member to be attached to an article to be supported, and a pair of props pivotally connected to said member and adapted to swing in opposite directions 105 away from each other into spaced relation longitudinally of said article to support the same, said props assuming a nested relation closely adjacent the side of said article when swung toward each other into inoperative 110 position.

3. A stand of the character described including a member to be attached to an article to be supported, and a pair of props pivotally connected to said member and adapted to swing in opposite directions away from each other into spaced relation longitudinally along the side of said article to support the same, said props being adapted to swing toward each other into a position snugly against the side of said article and one of said props receiving the other in a nested relation.

4. A stand of the character described including a member to be attached to an 125 article to be supported and provided with a pair of spaced pivot sleeves, and a pair of substantially U-shaped props having their arms pivotally connected to the respective ones of said sleeves and adapted to swing 130

longitudinally of said article away from each other into an operative position and toward each other into inoperative position, one of said props receiving the other within 5 itself in a nested relation when said props are disposed in an inoperative position.

5. A stand of the character described including a band adapted to be circumfer-

entially applied to an article to be supported and formed at its edges with opposite pivot 10 sleeves, and a prop pivotally connected to each of said sleeves to swing longitudinally of said article into spaced relation to support the same.

WILLIAM E. EDWARDS.
